(57) **CLAIM**

The ornamental design for a set of adhesive tapes, as shown and described.

DESCRIPTION

FIG. 1 is a top, front, right perspective view of a set of adhesive tapes, showing my new design; FIG. 2 is a bottom, rear, left perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; and, FIG. 9 is a front elevation view of the set of adhesive tapes of FIG. 1 showing the set of adhesive tapes partially peeled off of a backing sheet.

The broken lines of uneven length define the boundary of the claimed design and form no part of the claimed design.

1 Claim, 9 Drawing Sheets
